United States Patent Office.

GEORGE H. PERKINS, OF BROOKLYN, NEW YORK.

Letters Patent No. 104,193, dated June 14, 1870.

IMPROVEMENT IN METALLIC CAPS FOR TIN CANS.

The Schedule referred to in these Letters Patent and making part of the same

To all whom it may concern:

Be it known that I, GEORGE H. PERKINS, of the city of Brooklyn, in the county of Kings and State of New York, have invented certain new and useful Improvements in Mouth-Pieces or Caps for Metallic Cans; and I hereby declare in what manner the same is to be constructed.

In order that the public may be enabled to understand the nature of my said improvement, and that those who are skilled in the tinsmith's art may construct the same, I will describe it as follows, to wit:

Figure 1 is a vertical section of the top of a can having my improved mouth-piece or plug, A and A', with the ring R attached to the under side of the same.

Figure 2 is a top view of my thin sheet-metal cap, hood, or plug A and A' as shown when looking down upon the top thereof.

I am fully aware that my patent, No. 100,180, and dated on the 22d of February, 1870, fully covers the screw-ring, in combination with a thin sheet-metal jacket passing under and around the screw-ring or mouth-piece, so as to constitute a thin sheet-metal plug upon the inner or under side of the throat of the tin or other can. Hence, my present application is an improvement upon the said patent, from the fact that I do away with the male screw-plug, and secure the ring R, fig. 1, to the under side of the cap A and A', in such a manner that the thin sheet metal consti-

tutes the outer cap and only plug to the throat of the can, and which is on or about the level with the top of the can. And, by means of the above improved arrangement of the thin sheet-metal cap or plug A and A', I am enabled to use a plain ring in lieu of the screw-ring R, if preferred, and hence increase the rigidity and durability of the throat of the can at less labor and expense than any of the devices now in common use.

The novelty of my improvement consists in the arrangement of the thin sheet-metal cap or plug A and A', having a plain or threaded ring, R, secured to the under side thereof, to avoid the use of an additional male plug, at the same time producing a perfect seal or plug to the mouth of the can; therefore,

What I claim as my improvement, and what I wish to secure by Letters Patent of the United States, is—

A single-sheet-metal cap, A and A', in combination with a ring, R, secured to the under side of the sheet-metal throat-piece or cap A, to hold the spigot without leakage of the contents of the can, all arranged substantially as described and shown in the drawing.

In testimony whereof I hereunto subscribe my name in the presence of two witnesses.

GEO. H. PERKINS.
